ATTORNEY.

UNITED STATES PATENT OFFICE.

PETER MURRAY MCKAY, OF ROCKVILLE, COLLINGWOOD, NEW ZEALAND, ASSIGNOR OF
ONE-HALF TO RICHARD WILLIAM BRICKELL, OF MORNINGTON, NEW ZEALAND.

ARTIFICIAL ARM AND THE FITTINGS THEREFOR.

1,213,222.

Specification of Letters Patent. Patented Jan. 23, 1917.

Application filed August 21, 1916. Serial No. 116,027.

To all whom it may concern:

Be it known that I, PETER MURRAY MCKAY, subject of the King of Great Britain, residing at Rockville, Collingwood, New Zealand, have invented new and useful Improvements in Artificial Arms and the Fittings Therefor; and I do hereby declare the following to be a full, clear, and exact description of the same.

10 This invention has been devised primarily with the object of providing an artificial arm of the type adapted to fit over a stump, that will be of strong construction so that it may be adapted for heavy working such as 15 hammering, digging and the like operations, and embodying special means whereby a rubber hand, tools of various kinds, such as a hammer head, grips for holding digging implements, carpentering tools and the like, 20 and other appliances may be readily fastened in the arm end and tightly gripped thereby.

The invention also consists in some special and novel forms of appliances for attachment to the arm by means of which different articles and tools may be held and operated by the use of the arm.

In fully describing the invention reference will be made to the accompanying sheet 30 of drawings, in which:—

Figure 1 is a side elevation of the improved arm having a hammer attached thereto. Fig. 2 is a longitudinal section thereof, showing the stem or shank of the 35 hammer withdrawn. Fig. 3 is an end view, on an enlarged scale, of the socket end of the arm. Fig. 4 is a sectional elevation thereof, and Fig. 5 a back elevation thereof, both being on the same scale. Figs. 6 and 7 are 40 respectively plan and elevation of one of the improved gripping appliances for use with the arm shown. Figs. 8 and 9 are respectively similar views of an alternative form of such appliance.

45 The artificial arm is formed with the hollow socket *a* of the usual shape adapted to fit over the stump of the wearer's forearm, and is in this invention preferably made of a light metal such as aluminum. It is attached in the ordinary way to the upper

55 arm leather band *b* by means of straps *c*, such band also having the usual neck strap connection *b'*. As an additional means of attachment of the socket *a* to the band *b*, a length of webbing *d* may be provided to extend from the lower back edge of the band through a loop *d'* on the lower back edge of the socket and then upward to a strap *d''* by which it is fastened to the band near its upper end. The provision of this extra connection more effectively holds the socket in 60 position on the arm stump and permits of greater working strain being placed thereon.

To the outer end of the arm socket *a* is fixed a block of metal *e* of suitable shape 65 that is firmly held in position by means of the straps *e'* extending therefrom and preferably made integral therewith, one along the top and one along the bottom of the socket, as shown in Figs. 1 and 2 and fastened to the socket by riveting or otherwise. This block therefore forms a solid portion 70 with the socket. The block is pierced centrally with a screw threaded recess and in such recess is screwed a plug or nut *g* having 75 a central bore *f*. This bore extends right through the plug, its rear end being reduced in diameter so as to form a shoulder *f'* while its internal surface is grooved longitudinally with a number of grooves *h* arranged 80 at regular intervals apart around it and of even depth and width. Eight of these grooves are preferably employed. This plug may thus be removed when worn or damaged and a new one readily placed in 85 position to replace it. If desired it may be held from movement by a pinch screw *g'* (Fig. 4).

Pivoted to the back face of the block *e* is a short lever *j* that extends at its upper end 90 out through a slot in such block and is formed at such end into a finger push *j'*. This lever on its inside is formed along one edge with a curved depression *j''* (Fig. 5) and a spring *k* normally keeps the lever 95 drawn across so that the curve of such depression projects within one edge of the back end of the bore *f*.

Each fitting or tool for attachment to the arm is formed with a shank or stem *m* hav- 100

- ing a boss n fixed upon it near its end which boss is adapted to fit within the larger outer portion of the bore f and is provided with teeth n' at intervals apart around it and of 5 such a size as to correspond with and fit into the grooves h in the plug g , while the boss is made of such a length that its inner end will engage the shoulder f' at the inner end of the bore. The shank is continued beyond 10 the boss with a diameter such as to permit of it passing through the smaller end of the bore and is formed with a groove m' at a suitable point therein to permit of the lever j fitting into the groove when the boss is 15 pushed right in. The stem extremity is rounded, as shown at m^2 so that when inserted it will push the lever j aside until it has been fully inserted, when the lever under the influence of its spring k will spring into 20 the groove m' and thereby hold the stem from withdrawal. Thus when the stem has been inserted into the bore it is locked firmly therein and is kept from any rotation by the engagement of its teeth with the grooves in 25 the bore. The provision of the number of grooves and teeth shown in the drawings provides for the stem being inserted and held firmly at any desired angle. In this manner a solid jointing and locking of the tool stem 30 to the arm is obtained so that in combination with the solid outer end of the arm, heavy work may be carried out by the manipulation of the arm, such for instance as hammering by means of a hammer o 35 (Fig. 1) having a stem shaped as before described and attached to the arm in the manner mentioned. Other tools or devices such as a knife, a fork, a screw driver or a rubber hand may be similarly locked to the arm. 40 To release the fittings it is only necessary to push the lever j back by pressure on the push j' when the stem will be released from the lever and may be drawn out.
- The fitting shown in Figs. 6 and 7 is designed to allow of the handle of a shovel, hay fork, or other like appliance being firmly gripped and then worked by the artificial arm. It consists in a pair of jaws $p-p'$ pivoted together at r and claw shaped 45 to fit between one another as shown, and provided with handle extensions $s-s'$ beyond their pivot and with a strong spring s^2 extending between their handles and keeping the jaws normally closed. The stem or 50 shank m of this fitting is arranged to extend at an angle to the plane of the jaws so that when inserted in the arm, and a tool or implement handle is inserted between and gripped by the jaws, such handle will extend 55 60 in relation to the arm at the proper angle for the working of the tool. The angle may be varied at will by the provision made and already described, for the insertion and locking of the stem within the arm socket. The

gripping faces of the jaws $p-p'$ may be 65 scored or serrated, as shown, to aid their gripping action upon the tool or implement handle.

The alternative form of fitting shown in Figs. 8 and 9 is designed to afford a grip 70 for the operation of such tools as are required to be held in a line continuously with the plane of the fore-arm for their operation, as for instance to hold and work the crank of a boring brace or the handle of 75 a saw. In this form the stem m forms one of the handles of the jaws $p-p'$ and is disposed continuously therewith, the grip being opened and closed by pressure upon and release of the other handle. If desired, the 80 toothed boss n may be made to revolve loosely on the stem so that in working a tool at angles, the jaws may be able to accommodate themselves to the varying angles assumed. In such a case the boss will be held 85 between collars t fixed to the stem.

I claim:—

1. An artificial arm characterized by having its end formed with a metal block and provided with a plug screwed into a threaded aperture therein, such plug being formed with a central bore extending through it having grooves formed longitudinally along its internal peripheral surface to receive correspondingly toothed stems of fittings for 95 the arm, substantially as specified.

2. An artificial arm characterized by having its end formed with a metal block and provided with a plug screwed into a threaded aperture therein such plug being formed 100 with a central bore extending through it having grooves formed longitudinally along its internal peripheral surface, a stop at the inner end of the bore and a spring catch situated on the inside of the block and normally overlying one side of the bore, in combination with a stem having a boss adapted to fit into the bore and formed with teeth fitting the grooves therein and an extension beyond the boss adapted to project through 110 the bore and formed with a groove around it adapted to be engaged by the said spring catch, substantially as specified.

3. A fitting for an artificial arm of the class herein referred to consisting in a pair 115 of curved jaws pivoted together and provided with handles extending beyond their pivot and with a spring situated between such handles and normally keeping the jaws closed, and a stem or shank adapted to be 120 inserted and locked within the arm, extending at an angle to the plane of the jaws, substantially as specified.

4. A fitting for an artificial arm of the class herein referred to, consisting in a pair 125 of curved jaws pivoted together and having a stem or shank adapted to be inserted into and locked within the arm extending beyond

the pivot continuously with one of the jaws, a handle extending beyond the pivot from the other jaw and a spring situated between such stem or shank and handle, normally 5 keeping the jaws closed, substantially as specified.

In testimony whereof, I have signed this

specification in the presence of two subscribing witnesses.

PETER MURRAY McKAY.
